UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,263,345.

Specification of Letters Patent. Patented Apr. 16, 1918.

Application filed June 24, 1913, Serial No. 775,479. Renewed February 15, 1918. Serial No. 217,463.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 This invention relates to a timing controller for governing the period of closure of a switch, which controls the activity of a motor in driving the computing mechanism of a combined typewriting and computing machine of the type shown in my application, No. 753,254, filed March 10, 1913, on which this is an improvement.

In the above-mentioned application, at the actuation of a numeral key to start a computation, various mechanisms were set in motion under the propulsion of an electric motor, so as to complete this computation and run it up in a computing head. The motor was of the intermittent type, 25 the electric circuit to the motor being completed at the striking of each numeral key by closing a switch in the form of two contacts movable into engagement with each other. When the computation was completed after the numeral key had returned to normal position, the circuit was broken by a parting of the contacts and the motor stopped until the next numeral key initiated another computation.

30 Now, it is possible that the tens-carrying mechanism, which must get in its work subsequent to the passing from nine to zero in a computing wheel in the computing head, might not be completed by the time the number is run up in its proper dial or computing wheel. For example, if "99,999,999" were exhibited in a computing head and one were added in the units place, it can very readily be seen that the extent of rotation required to add this one would be very slight, and yet the tens-carrying mechanism must subsequently perform its work, not only to carry from the units wheel to the tens wheel, but also *seriatim* from the tens 45 to the hundreds, from the hundreds to the thousands, and so on throughout the whole row of computing wheels. This, then, would take a considerable rotation of the tens-carrying mechanism in excess of that re-

quired for the mere running up of a number in the particular computing wheel in action. It is therefore necessary in some instances, to keep the motor running subsequent to the bare running up of the number.

In the present case I have provided a timing controller, which prevents the breaking of the circuit to the electric motor immediately after the bare running up of the number has been completed, and the functions of the mechanism necessary to this running up interrupted. To accomplish this, I provide a retarder which is connected to the movable contact of the switch and tends to delay the return or breaking movement of this contact even after the positive means, which is actuated at the striking of a numeral key to make the connection, has been removed from engagement with this movable contact.

Other features and advantages will hereinafter appear.

In the accompanying drawings—

Figure 1 is a fragmentary skeleton perspective view showing the improvement in connection with such details of the other mechanism as are thought necessary to illustrate the application of the same and showing the circuit in its open or broken condition.

Fig. 2 is a detail showing the contacts of the electric switch brought into engagement with each other, so that the circuit to the motor is completed.

Fig. 3 is a detail of the tripping mechanism for the shaft which aids in completing the computation after the initiation of the same by the striking of a numeral key.

Fig. 4 is a detail section of the retarder or controller.

Referring more particularly to the separate parts of this invention as embodied in the form shown in the drawings, 1 indicates numeral keys, which actuate the usual type actions to write on the work-sheet carried by the typewriter carriage (not shown). In addition to performing the writing of the numbers, the numeral keys 1 depress levers 2 to pull on links 3 and thus rock bell cranks 4 to draw on links 5, which are connected at their opposite ends to rock levers 6, connected to shift interponents 7 into the path of an actuator 8, shown in the form of a frame including two spaced rings

9 and 10, in which the particular interponent 7 in action is cradled for a back-and-forth movement. The interponents 7 are for the purpose of setting apposite pins 11 5 in an index or valuating wheel 12, which determines the extent of rotation of the shaft of the wheel to correspond with the value of the particular numeral key actuated. The interponents 7 are not themselves actually forced by the levers 6 to set the pins 11, but power is supplied to the actuator or cradle 8 in one direction from a shaft 13, and in the other direction by a spring 14. For this purpose, the cradle or actuator 8 is connected to a rod 15, having a spring 14 mounted on one end thereof, and connected to the shaft 13 at the other end by means of a link 16, and a cam arm 17 fixed on the shaft 13. 10 The shaft 13 receives its motion from a spring 18, which forms a sort of auxiliary motor, and acts to drive a rack bar 19 having a rack 20 meshing with a gear 21 fixed to the shaft 13. The rack bar 19 performs certain other functions, such as locking a computing head 22 against movement by rocking a lock 23 to bring the toe thereof into engagement with a rack 24 carried by the computing head 22. This is accomplished by a rack 25 on the rack bar 19 engaging a segment 26 carried by the shaft of the lock 23. The shaft 13, however, is normally held against rotation by means of a detent 27, which engages a five-toothed 15 ratchet wheel 28 secured to the shaft 13 and held against counter-rotation by a spring-pressed pawl 29. At each actuation of a numeral key, however, the detent 27 is tripped by means of a tripper 30, which engages an adjustable stop 31 on the detent 27 and is actuated by a lever 32, which in turn is actuated by a disk 33 universal to all of the levers 6. 20 It will thus be seen that when any one of the numeral keys 1 is depressed, it rocks the corresponding lever 6, which in turn slides the universal disk 33 rearwardly against the tension of a spring 34, so that the lever 32 will be rocked to plunge the tripper 30 against the stop 31 on the detent 27, releasing the wheel 28 so that it is permitted to rotate under the propulsion of the spring 18, which has been previously tensioned. 25 In addition to the functions just mentioned, the shaft 13 unsets the previously set pin by means of a cam 35 engaging a resetting finger 36, which is located with its upper end in register with the previously set pin. This set pin leaves a blank or vacant space in the series of pins 11 on the valuating wheel 12, so that a spur wheel located at this point, which is intended to rotate the wheel 12, will rotate idly if it 30 itself is rotated. The spur wheel is not

illustrated here; however, it is mounted on a shaft 37, which is provided with a loose bevel gear 38 driven by a bevel gear 39.

To connect the bevel gear 38 in driving relation with the shaft 37, there is provided 70 a clutch 40, which is rendered effective by a shifting arm 41 also actuated on the rotation of the shaft 13 by a spring 42, which is normally held against action because of a finger 43 on the shifting arm 41 engaging 75 the cam 35, which on the rotation of the shaft 13 passes from beneath this finger, permitting the spring 42 to act. The bevel gear 39 is mounted on a shaft 44, which is driven from an electric motor 45 by means 80 of intermeshing bevel gears 46 and 47, the latter of which is on the motor shaft.

When the valuating wheel 12 is rotated by the mutilated gear comprising the pins 11 being completed at the point of mesh 85 with a driving spur on the shaft 37, then it itself in turn rotates through a mechanism, not shown, a shaft 48, which may rotate either one of a pair of loose bevel gears 49 and 50, according to the position of a double clutch 51 splined on the shaft 48 between the gears 49 and 50. These gears 49 and 50 alternatively rotate a bevel gear 52 mounted on a master wheel shaft 53, which is provided with a master wheel located within 90 the computing head 22 and arranged to rotate the computing wheels thereof individually and *serialiter*, a relative step-by-step movement being provided between the master wheel and the computing wheels in any 95 suitable manner.

In addition to driving the valuating or index wheel 12, the shaft 44, which is driven from the motor 45, drives an intermediate shaft 54, by means of meshing bevel gears 55 and 56, the latter of which is on the shaft 44 and the former of which is on the shaft 54. This shaft 54 in turn drives a shaft 57, through the intermediary of a pair of intermeshing bevel gears 58 and 59. The shaft 105 57 in turn drives the tens-carrying mechanism for the computing head 22 through a similar arrangement of gears such as that shown in connection with the master-wheel shaft 53.

After a computing action has been completed, it is necessary to retension the spring 18 and restore the parts to their normal condition ready for a subsequent computing operation. For this purpose, a shifter 60 is 110 moved up on the initial movement of the valuating wheel 12 in the manner described in my above mentioned application, so that an arm 61 thereon comes to a position to be actuated by the just set pin 11 when it 115 comes to a home position corresponding to the presenting of a blank space to the driving spur wheel on the shaft 37. In moving to this position, the shifter 60 engages over the hook of a latch 62 on a clutch closer 63. 120 125 130

The clutch closer 63 engages one element of a clutch 64 fixed on the shaft 54 and arranged to be brought into mesh with a corresponding clutch element 65 loose on the 5 shaft 54 but connected to a sleeve 66. These clutch elements, however, are normally held apart by a spring 67, so that the sleeve 66 is normally silent. When the valuating wheel 12 comes to rest, the just set pin 11 thereon 10 engages the arm 61 and rocks the shifter 60, so that the clutch closer 63 is also rocked against the tension of the spring 67, thereby bringing the clutch elements 64 and 65 together to drive the sleeve 66.

15 On the sleeve 66, there is provided a cam 68, which when the sleeve 66 is rotated, will engage a follower 69 on a bell crank 70 to rock the same against the tension of a spring 71. The bell crank 70 is connected by a lug- 20 and-slot connection 72 to the rack bar 19, so that it will depress the same, retension the spring 18, and restore the shaft 13 and the parts connected thereto to their normal set positions ready for a subsequent opera- 25 tion; this counter-rotation of the shaft 13 being permitted in spite of the pawl 29 and the ratchet wheel 28, by a one-way connec- 30 tion 73, which connects the ratchet wheel 28 to the shaft 13. At the end of this ac- 35 tion, the latch 62 of the clutch closer 63, is disengaged from the shifter 60 by a du- 40 plex cam 175 on the sleeve 66 engaging the latch 62 and tripping it from engagement with the shifter 60, permitting the latter 45 and the clutch closer 63 to return to their normal positions, thus interrupting the clutch connection between the shaft 54 and the sleeve 66.

Now, in order to enable the motor 45 to 40 drive all these mechanisms, it is first necessary to pass an electric current through the same as this motor is normally silent. For this purpose, as soon as the shaft 13 is per- 45 mitted to rotate under the propulsion of the previously tensioned spring 18, it closes a switch 74, which is connected by circuit 50 wires 75, to the motor 45. To do this, the cam arm 17 on the shaft 13 engages a fol- 55 lower 76, which is mounted on a pivotally supported lever 77 and is further connect- 60 ed to a link 78, so as to draw on the same. This link in turn swings an arm 79 to rock a shaft 80 carrying an arm 81. The arm 81 underlies a pin 82 on a switch arm 83 which 65 is loosely pivoted on the shaft 80. The switch -arm 83 is provided with a bearing roller 84 of some insulating material, which engages the lower contact 85 of the switch 74 and forces it up into engage- 70 ment with the upper contact 86 of this switch. The contacts 85 and 86 being made of flexible material admit of a certain amount of springy or yielding motion when forced into engagement with each other by 75 the switch arm 83.

It will thus be seen that concomitantly with the striking of a numeral key to effectively set one of the pins 11, the circuit to the electric motor 45 is completed.

If, then, a number is run up in the com- 70 puting head and the sleeve 66 rotated to return the shaft 13 and the parts carried thereby to their normal initial positions, the follower 76 will likewise be returned to its normal position. This is accomplished 75 by the bell crank 70 when rocked, rocking the lever 77 through the intermediary of a link 87, which is connected at one end to the bell crank 70 and at the other end to the lever 77. The follower 76 in turn rocks the 80 bell crank comprising the arm 79, the shaft 80 and the arm 81, so as to withdraw the arm 81 from beneath the pin 82, permitting the switch arm 83 to return under its own weight and the slight tension of the con- 85 tacts 85 and 86. The return of the arm 83 and the opening of the switch 74, however, are delayed momentarily by a retarder or controller 88, shown in the form of a dash- 90 pot. This retarder comprises an outer cyl- 95 inder 89, having an annular groove 90, in which the forked end of the switch arm 83 engages. The cylinder 89 fits somewhat loosely on a plunger or piston 91, so that in case of a collapsing movement the air 95 will be entrapped between the piston 91 and the cylinder 89 and yet will pass slowly out between them, admitting of a slow relative movement, which delays the breaking of the circuit to the motor 45.

The making of the circuit, however, must be quickly accomplished, as the motor must be connected up almost instantly with the striking of a numeral key. For this purpose, the piston plunger 91 is reduced at 92 100 to admit a rather large volume of air to pass between the piston and the cylinder 89, which reduced portion forms an annular chamber communicating at all times, at 93, with the outside atmosphere, the piston 91 110 always being spaced apart somewhat from the base or support 94 of the plunger 91. The reduced portion 92 forming the chamber between the piston 91 and the cylinder 89 communicates with a cavity 95, which 115 also communicates with a passage 96. The passage 96 is normally closed by a ball valve 97, which is held on its seat by a spring 98. The spring 98 abuts at its upper end against an inwardly-turned annular flange 99, and 120 at its lower end against the ball valve 97. When the cylinder 89 is raised relatively to the plunger or piston 91, the ball valve 97 will be sucked up against the tension of the spring 98, uncovering the passage 96, so that 125 communication is opened between this pas- 130 sage and a passage 100, which communicates with the top of the internal bore or chamber of the cylinder 89, permitting the air to enter rapidly and thus preventing any re- 135

1. Tardation of the upward movement of the cylinder 89, which movement corresponds to the closing of the circuit to the electric motor 45.
5. It will thus be seen that while the electric circuit to the motor may be quickly made at the striking of a numeral key, the breaking of this circuit will be delayed after the number corresponding to the numeral key actuated has been run up in the computing head, so that in case an ext a amount of rotation is needed for tens-carrying, the motor 45 will be running and the tens-carrying mechanism still rotated.
10. Variations may be resorted to within the scope of the invention, and portions of the improvements may be used without others.
15. Having thus described my invention, I claim:
20. 1. In a computing machine, the combination with computing mechanism including valuating and carrying mechanisms, of an intermittently operative source of power for operating said valuating and carrying mechanisms, and means for effecting complete carrying at all times by prolonging the operation of said source of power after it has completed the operation of the valuating mechanism.
25. 2. In a computing machine, the combination with computing mechanism, including valuating and carrying mechanisms, of an intermittently - operable motor for driving said carrying and valuating mechanisms, connections from said motor to said mechanisms, and means to control said connections so that the carrying mechanism is driven by said motor for a longer time than the valuating mechanism.
30. 3. The combination with a computing mechanism, including carrying mechanism, of means for insuring complete carrying at all times, said means including numeral keys for controlling the action of said computing mechanism, a motor for driving said computing mechanism, a circuit to said motor, a switch for closing said circuit, a switch arm for manipulating the parts of said switch, means for positively actuating said switch arm at the actuation of a numeral key, and a retarder connected to said switch arm for delaying the return movement of the same after said positive means has been withdrawn from engagement with said switch arm, whereby the operation of the motor on the carrying mechanism is prolonged.
35. 4. In a computing machine, the combination with a computing mechanism, including valuating mechanism and carrying mechanism, of an electric motor including a circuit for driving said valuating and carrying mechanisms, means for quickly making said circuit to start said motor to actuate said valuating and carrying mechanisms, means to quickly break the connection between said motor and valuating mechanism on completion of the valuating operation, and means to prolong the circuit closure after the connection from said motor to said valuating mechanism is broken to insure complete operation of said carrying mechanism.
40. 5. The combination with a computing mechanism including a valuating mechanism, of a motor for driving said computing mechanism, a circuit to said motor, a switch for closing said circuit, a switch arm for manipulating parts of said switch, numeral keys for positively actuating said switch arm, means brought into action on completion of the movement of said valuating mechanism for withdrawing said positive means from engagement with said switch arm, and means for delaying the movement of said switch arm to open said circuit after said positive means has been withdrawn.
45. 6. The combination with a computing mechanism, including a valuating mechanism, of an intermittent motor for driving said computing mechanism, a circuit to said motor, a pair of contacts for controlling the make and break of said circuit, a switch arm connected to one of said contacts to manipulate the same, a pin on said arm, a second arm engaging said pin and manipulating said switch arm, numeral keys controlling the movement of said second arm, so as to move said switch arm to close said circuit, means brought into action on the completion of movement of said valuating mechanism for withdrawing said second arm from said pin, and means for delaying the movement of said switch arm to open said circuit after said second arm has been withdrawn from said pin.
50. 7. The combination with computing mechanism, including valuating mechanism, of an intermittently-acting motor for driving said computing mechanism, a circuit to said motor, a pair of contacts for controlling the make and break of said circuit, a rock shaft, numeral keys, means for rocking said shaft at the actuation of any of said numeral keys, an arm fixed to said rock shaft, a switch arm loose on said rock shaft, a pin on said switch arm engageable by said fixed arm to rock said rock shaft, said switch arm engaging one of said contacts to control the make and break of said circuit, means controlled by said valuating mechanism for moving said fixed arm away from said pin, and means for retarding the return movement of said switch arm after said switch arm has moved away from said pin.
55. 8. The combination with a computing mechanism including valuating mechanism having an action coordinate with the computing of a number, of an intermittently-acting motor for driving said computing mechanism, numeral keys for controlling the

action of said computing mechanism, a normally open circuit to said motor, means for closing said circuit at the actuation of said numeral keys, and means for delaying the opening of said circuit for a period subsequent to the completion of the functions of said valuating mechanism necessary to the computing of a number.

9. The combination with a computing mechanism and numeral keys, of a motor for driving said computing mechanism amounts as determined by said keys, a circuit to said motor including a pair of contacts, a switch arm engaging one of said contacts to close said circuit, a lever operated by any key for manipulating said switch arm, said lever operating said switch arm by direct contact therewith and moving away from said switch arm to permit the breaking of said circuit, and a drag connected to said switch arm to delay the opening of said circuit for a period subsequent to that determined by said lever, whereby the functions of computing, including carry-

ing of numbers from lower to higher orders, 25 may be fully performed.

10. In a computing machine, the combination with computing mechanism, including valuating mechanism, of an intermittently-acting motor, a circuit for said motor, 30 computation-determining means for closing the motor circuit to start a computation, connections between the motor and said computing mechanism, disconnecting means in said connections, devices for operating said 35 disconnecting means at the completion of the valuating operation and to restore certain parts of the computing mechanism to normal position, said devices also acting to initiate the breaking of said motor circuit, 40 and means for retarding the breaking of said circuit to insure certain parts of said devices being properly positioned for a subsequent operation.
